(57) **CLAIM**

The ornamental design for a shoe, as shown and described.

DESCRIPTION

FIG. 1 is front left perspective view of a shoe showing our new design according to an exemplary embodiment; FIG. 2 is front view of the design shown in FIG. 1; FIG. 3 is a rear view of the design shown in FIG. 1; FIG. 4 is a right side view of the design shown in FIG. 1; FIG. 5 is a left side view of the design shown in FIG. 1; FIG. 6 is a top view of the design shown in FIG. 1; and, FIG. 7 is a bottom view of the design shown in FIG. 1. The broken lines shown in the figures are included for the purpose of illustrating portions of the shoe that form no part of the claimed design. The material shadings shown in the figures represents a knitted textile and forms a part of the claimed design.

1 Claim, 6 Drawing Sheets
